(57) **CLAIM**

An ornamental design for a jewelry article, as shown and described.

DESCRIPTION

FIG. 1 is a front perspective view of a first embodiment of a jewelry article showing our new design;

FIG. 2 is a front elevation view thereof;

FIG. 3 is rear elevation view thereof;

FIG. 4 is right-side elevation view thereof;

FIG. 5 is a left-side elevation view thereof;

FIG. 6 is a top view thereof;

FIG. 7 is a bottom view of thereof;

FIG. 8 is a perspective view thereof;

FIG. 9 is a front perspective view of a second embodiment of a jewelry article;

FIG. 10 is a front elevation view thereof;

FIG. 11 is a rear elevation view thereof;

FIG. 12 is a right-side elevation view thereof;

FIG. 13 is a left-side elevation view thereof;

FIG. 14 is a top view thereof;

FIG. 15 is a bottom view thereof;

FIG. 16 is a perspective view thereof;

FIG. 17 is a front perspective view of a third embodiment of a jewelry article;

FIG. 18 is a front elevation view thereof;

FIG. 19 is a rear elevation view thereof;

FIG. 20 is a right-side elevation view thereof;

FIG. 21 is a left-side elevation view thereof;

FIG. 22 is a top view thereof;

FIG. 23 is a bottom view thereof;

FIG. 24 is a perspective view thereof;

FIG. 25 is a front perspective view of a fourth embodiment of a jewelry article;

FIG. 26 is a front elevation view thereof;

FIG. 27 is a rear elevation view thereof;

FIG. 28 is a right-side elevation view thereof;

FIG. 29 is a elevation view thereof;

FIG. 30 is a top view thereof;

FIG. 31 is a bottom view thereof;

FIG. 32 is a perspective view thereof;

FIG. 33 is a front perspective view of a fifth embodiment of a jewelry article;

FIG. 34 is a front elevation view thereof;

FIG. 35 is a rear elevation view thereof;

FIG. 36 is a right-side elevation view thereof;

FIG. 37 is a left-side elevation view thereof;

(Continued)

FIG. 38 is a top view thereof;
 FIG. 39 is a bottom view thereof;
 FIG. 40 is a perspective view thereof;
 FIG. 41 is a front perspective view of a sixth embodiment of a jewelry article;
 FIG. 42 is a front elevation view thereof;
 FIG. 43 is a rear elevation view thereof;
 FIG. 44 is a right-side elevation view thereof;
 FIG. 45 is a left-side elevation view of thereof;
 FIG. 46 is a top view thereof;
 FIG. 47 is a bottom view thereof;
 FIG. 48 is an alternative perspective view thereof; and,
 FIG. 49 is another perspective view thereof.
 The broken lines shown in the drawings illustrate portions of the jewelry article that form no part of the claimed design. The broken lines showing a wrist and hand illustrate environmental subject matter and form no part of the claimed design.

1 Claim, 32 Drawing Sheets
